UNITED STATES PATENT OFFICE

ABRAHAM GOODMAN AND JACOB GOODMAN, OF BROOKLYN, NEW YORK

DOUBLE HAIR WAVER

Application filed December 26, 1929. Serial No. 416,311.

This invention relates to improvements in hair wavers, more especially to those of the type described in a patent granted to us on March 12, 1929, numbered 1,704,378.

Devices of this type must be constructed of very cheap material, the manufacturing should be very simple, and there must be a minimum of parts. These characteristics are vital because devices of this sort must be sold cheaply. Moreover, it is further necessary to have the hair wavers made strongly, in order that they carry out their functions efficiently and render long service.

It is the object of this invention to devise a double waving device of the type described in the above mentioned patent, to have the same composed of a minimum of parts, and yet produce an article which will be efficient and of enduring construction. Our invention discloses an ideal embodiment intended to comply with all of the foregoing requirements.

Referring to the drawings where a preferred form and a modification of our invention are shown:—

Figure 1 is a plan view of the device.

Fig. 2 is a side view.

Fig. 3 is a section along line 3—3 of Fig. 1.

Fig. 4 is a section on the line 4—4 of Fig. 1, and,

Fig. 5 is a plan view of a modification.

Reference numeral 10 indicates a wire-like element bent to form a loop having parallel sides 11 and 12, and a constricted or crimped portion 13. Each of the parallel portions 11 and 12 terminate respectively in ends 14 and 15 which are coiled about a thin flanged sleeve 16.

There are two of these loop members 10, and in cooperation with these members we have a U-shaped loop 17 having parallel portions 18 and 19. These parallel portions terminate in ends 20 and 21, each of which is loosely coiled about a sleeve 16 between the coiled ends 14 and 15 of the loops 10. This construction allows for relative pivotal movement between members 10 and the U-shaped loop 17.

The two sleeves 16 are mounted on a rivet 22 and are held in spaced relation by a sleeve

23. The rivet is headed over a pair of rings 24 and securely holds the loops in assembled position relatively thereto. A plate 25 may be used to hold the loops 10 in fixed relation at their other extremity, but this plate may be disposed of if it is desired to secure a more flexible device with each loop 10 cooperating independently with the U-shaped loop 17 as shown in Fig. 5.

The rivet 22 and the crimped ends 13 of each loop are preferably raised with respect to the parallel portions 11 and 12. The U-shaped loop 17 is adapted to enter the constricted or crimped portions 13 to form a resilient lock for maintaining the parts in the position of Fig. 1. Because of the raised relation of the pivot and the portions 13, the portions 18 and 19 will occupy a raised position relatively to the portions 10 and 11 so as to give the proper hair waving effect.

From the above description, the operation and construction of our device should be clear. Although we have described but one embodiment of the invention, modifications of the same within the scope of the appended claims may readily occur to one skilled in the art.

What we claim is:—

1. An article of the class described comprising a pair of members each of a wire like element bent to form a loop with parallel portions terminating in adjacent coiled ends, a second loop member having parallel portions terminating in coiled ends positioned between the coiled ends of each of the pair of members, a rivet extending through all of said coiled ends for maintaining the same attached as in service and providing a pivot, said members being adapted for relative pivotal movement on said rivet so that end portions of the second member may be moved between the parallel portions of the first members, and cooperative locking portions on said members in engagement with each of said pair of members.

2. An article of the class described comprising a pair of members each formed of a wire like element bent to form a loop having a crimped end portion and parallel portions terminating in adjacent coiled ends, a sec-

ond loop member having parallel portions terminating in coiled ends positioned between the coiled ends of each of the pair of members, a rivet extending through all the said coiled ends for maintaining the same attached as in service and providing a pivot, spacing means on said rivet for holding said members in proper space relation, said members being adapted for relative pivotal movement on said rivet so that each parallel portion of the second member may be moved between the parallel portions of the first members and a part thereof into locking engagement with the crimping portions of said pair of members, said crimping portions and the pivoting rivet being raised with respect to the parallel portions so that the second member has an elevated position with respect to the parallel portions of each of said first members when in locking engagement with the crimped portions thereof.

ABRAHAM GOODMAN.
